UNITED STATES PATENT OFFICE

ARCH K. WOOD, OF JEANNETTE, PENNSYLVANIA, ASSIGNOR TO MCKEE GLASS COMPANY, OF JEANNETTE, PENNSYLVANIA, A CORPORATION OF PENNSYLVANIA

ILLUMINATED SIGN

Application filed February 17, 1930. Serial No. 428,884.

My invention relates to improvements in the glass letters and characters which constitute elements in illuminated signs, of the sort commonly displayed for advertising purposes along the streets of cities. The object of my improvements is economy in production.

The invention is illustrated in the accompanying drawings, in which Fig. I is a view in perspective of the article with which the invention has to do; Fig. II is a diagrammatic view in side elevation of a mold employed in the production of the article, as in the practice of my invention I produce it; Fig. III is a view in section, on the plane indicated by the line III—III, Fig. II; Fig. IV is a view similar to Fig. III, and illustrating a modification in mold structure.

The article with which I have to do, illustrated in Fig. I, is a now familiar article of commerce. It consists of a sheet of glass 1 of translucent nature, commonly opal glass. The sheet ordinarily is about an eighth of an inch thick and may be of a few inches in length and breadth—say six inches by eight. The otherwise level sheet is embossed: portions are raised to form embossed characters, ordinarily in the form of a letter 2, and so adapted to enter into the make-up of a legible sign. In the make-up of the article the sheet of glass is arranged behind a mask of sheet metal in which spaces have been cut, after the manner of a stencil-sheet. The spaces in the mask correspond in shape, size, and position to the embossed portions of the sheet of glass. In the assembly the embossed characters extend into and project from the spaces in the mask, and those portions only of the glass sheet, illuminated from behind, are visible, and, being visible, constitute the effective part of the sign.

Ordinarily such a sheet as in an exemplary way is illustrated in Fig. I is formed initially as a smooth and unembossed sheet. The sheet after it has been formed is laid upon a shaper-block of iron or steel provided with a smooth face, from which the desired character rises in relief. To this shaper-block the initially level and continuous sheet is, under the softening influence of flame, caused to

shape itself. Having been so shaped, the sheet is allowed to harden again. This procedure involves the initial shaping and the annealing of the level sheet, and then the subsequent reshaping of the sheet to produce the raised character or characters, and the necessarily ensuing second annealing. Alternatively, the article of Fig. I may be shaped in a mold, but unless the mold faces be formed of such superior material and finished with such laborious care as to be very expensive, the outer or raised surface of the molded article will have to be fire-polished to prepare it for service. The exposed outer or raised surface of the article must be exceedingly smooth. The article of my invention is in this and in all other respects of best quality and is produced more economically than an equally good article may otherwise be produced.

I blow the article in a mold, the ultimate outer or raised surface innermost, shaped under pneumatic pressure, free of contact with any mold wall, and consequently of unblemished smoothness, and I form the mold wall to include a smooth face from which the desired character rises in relief. And in a single shaping step I produce from the plastic glass the ultimate shape. Since it is the ultimate inner surface of the sheet which is formed in actual contact with the mold wall, that wall need not be formed of such costly material so laboriously finished as would be requisite if it were the ultimate outer surface which was formed in actual contact with it. The mold, therefore, may be a relatively inexpensive one.

Turning to Figs. II and III, a mold structure is shown which includes panels 3, whose inner faces form part of the inner surface of the mold cavity. These faces are smooth and from their smooth faces the desired characters rise in relief, as indicated at 4. A gather of glass blown to the thickness of a sheet within this mold cavity, as indicated at 5, is shaped to the inner faces of the panels 3. At the edges the panels may be formed with sharp-edged protrusions 6, which will form in the blown article lines of weakness. When the article has been blown and has set within

the mold, the mold may be opened, and then the article of Fig. I, produced in this single blowing operation may be severed from the remainder of the blown article. That face 5 of the finished article of Fig. I from which the character 2 rises is the face which is formed under the pneumatic pressure of the blowing operation, free of contact with any solid wall, and is of unblemished smoothness.

10 I characterize this a blown surface.

Figs. II and III show that the panel 3 may be removable and replaceable as a member of the mold wall, to the end that, using a single mold frame, interchangeability of a 15 plurality of mold panels 3 may afford capacity to produce sign elements bearing a variety of particular characters—the several letters of the alphabet, for example.

Fig. III shows a convenient arrangement, 20 of a narrow-chambered mold, with two panels 3 set in opposite walls, and each adapted to produce a sign element such as that shown in Fig. I, with choice of what the particular character may be. Fig. IV shows a mold of 25 rectangular cross-section having such panels let into each of its four walls; and from this variety in showing it will be manifest that the mold chamber may be variously shaped, and with variety in the number and position 30 of the panels 3.

I claim as my invention:

An element for an illuminated sign consisting of a plate of glass in which is formed a character in relief, the outer surface from 35 which the character rises being a blown surface.

In testimony whereof I have hereunto set my hand.

ARCH K. WOOD.
